HAT MACHINERY

Ralph K. Reynolds, Danbury, Conn., assignor to
The Mallory Hat Company, Danbury, Conn., a
corporation of Connecticut

Application April 19, 1934, Serial No. 721,345

15 Claims. (Cl. 28—5)

This invention relates to hat machinery and more particularly to spraying apparatus for a starting machine or the like.

One of the objects of this invention is to provide spraying apparatus which may be easily manufactured with inexpensive materials and low cost of labor. Another object is to provide apparatus of the above character which will be strong, practical and thoroughly durable. Another object is to provide apparatus of the above character which may be easily installed in machines of different designs now in common use without material structural alterations. Another object is to provide apparatus of the above character which may be easily operable without interrupting the normal functions of an operator of a starting machine. Another object is to provide apparatus of the above character which may be supplied with fresh water free from damaging impurities. Another object is to provide apparatus of the above character which, by its use, will not damage the hat bats being sprayed. Another object is to provide apparatus of the above character which will utilize waste heat from other portions of the machine. Other objects will be in part obvious and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawing, in which is shown one of the various possible embodiments of my invention,

Figure 1 is a perspective view of a starting machine or the like having my apparatus installed therein;

Figure 2 is a vertical sectional view partially fragmentary, taken along the line 2—2 of Figure 1;

Figure 3 is a vertical sectional view taken along the line 3—3 of Figure 1, and

Figure 4 is a sectional view of a valve which forms a part of my apparatus.

Similar reference characters refer to similar parts throughout the several views of the drawing.

As conducive to a clearer understanding of certain features of this invention, several difficulties now met with in hat manufacture will be pointed out. As an introduction to the sizing operation, hat bats are first subjected to a "starting" process, the details of which will be

more clear from the description to follow. One of the operations incident to the most efficient practice of the starting process is that of sprinkling groups of bats with hot water or the like. This is usually accomplished by dipping a scrub brush or the like in a tank of boiling water and subsequently shaking it over the group of bats to sprinkle the water thereon. This cumbersome operation is accompanied by some very practical difficulties. The continued rolling of bats on the bench of the machine when they are in a loose and fragile condition, causes small clots of fur to gather on various portions of the bench which are gradually washed down into the tank. When the brush is dipped in the tank it often picks up such particles of fur and, during the subsequent shaking thereof, these small clots of fur are deposited on the bat. This is very injurious to the hat bat and usually causes the formation of what is known in the art as a "dag", a small bump of felt in the finished hat which is not only unsightly but weakens the entire hat structure. Further still, it is difficult to control the quantity of water dropped upon the bat by the brush and the force with which it is dropped. Also, unless the operator is careful, the water will be unevenly distributed about the hat bat. All of these factors often serve to damage the hat bat so materially during this sprinkling operation that at a later time the bat must be discarded. For example, if too much water is dropped from the brush on one portion of the bat when it is in its loose condition, it may wash away some of the fibers or distribute them unevenly on that portion of the bat thus making a weak section in the resultant hat. One of the objects of this invention is to provide apparatus which will successfully and practically overcome these difficulties as well as many others.

Referring now to the drawing in detail, there is shown in Figure 1 a starting machine including a table generally indicated at 10 within which is supported a tank generally indicated at 11 for holding hot water or the like. Tank 11 is supplied with water in any suitable manner, this water being heated by a variety of methods but preferably by forcing live steam therethrough. Secured to the front legs 10a and 10b of table 10 are a pair of bracket members 12 and 13 supporting a bench 14 which preferably slopes upwardly from the top of tank 11 so that any water which may gather thereon runs into the tank. Preferably the sides of bench 14 are bordered by a ridge 15 for pre-

venting water from spilling onto the floor in undue quantities.

A pair of supports 16 and 17 extend above tank 11 and have rotatably mounted therein a pair of rolls 18 and 19 preferably power driven in any suitable manner as, for example, by way of a pulley wheel 20. Rolls 18 and 19 may be of any desired character suitable for carrying out the starting operation.

10 During the practice of the starting operation, the bats, usually in groups of three, are placed upon a cloth on bench 14, rolled into bundles, dipped in the tank 11, and placed between the rolls 18 and 19. However, before the bats are 15 rolled into bundles, it is desirable to sprinkle them with a delicate shower of hot clean water.

For this purpose I provide a pipe coil 21 suitably disposed within tank 11 and preferably so arranged as to be more or less completely covered by the hot water held by the tank. One end 21a of coil 21 is connected to the outlet port 22 of a valve generally indicated at 23. Although valves of many different constructions might be used for this purpose, I prefer to provide a 25 valve of the general type shown in Figure 4. Thus valve 23 has an upper chamber 24 connected to outlet port 22 and a lower chamber 25 connected to an inlet port 26. Chambers 24 and 25 are in turn connected by way of a port 27 forming a seat for a head 28 having a stem 28a extending through chamber 24 and out through the top of the valve. A spring 29 is disposed between the bottom of chamber 25 and head 28 thus to normally hold head 28 firmly against 35 the seat thereof and prevent passage of water from chamber 25 to chamber 24. Spring 29 may be held in position by a pair of lugs 30 and 31 located respectively on the bottom of chamber 25 and the bottom of head 28. Inlet port 26 is 40 connected to a suitable source of water by way of a conduit 32.

A lever 33 is pivotally connected to a stud 34 on the top of valve 23 and is in engagement with stem 28a. Preferably leg 10a (Figure 1) 45 of table 10 has pivotally connected thereto a foot pedal 35 which is connected to the outer end of lever 33 by a suitable connector 36. Accordingly downward pressure of pedal 35 depresses stem 28a to allow passage of water 50 through valve 23, and release of that pressure allows spring 29 to force head 28 against its seat and prevent any further passage of water 55 therethrough.

Turning now to Figures 1 and 2, end 21b of 55 coil 21 is connected to a tubular member 37. Tubular member 37 is preferably located in the left-hand side of bench 14 as the operator faces the machine. Member 37 may be secured in this position in any desirable manner as, for example, by way of a pair of bracket members 38 and 39 attached to the bench. As best shown in Figure 2, member 37 is provided with a drain 40 in its lower end through which water therefrom may drain back into tank 11.

60 Formed in the side of tubular member 37 facing bench 14 is a plurality of holes generally indicated at 41. Holes 41 may be arranged in any suitable manner to direct a shower of water evenly on all portions of a group of bats generally indicated at 42 placed upon the bench 14 for the starting operation. For this purpose, however, I prefer to provide four rows of holes A, B, C and D as best shown in Figures 1 and 3. The lower row D (Figure 3) is almost parallel 70 to a plane passing through the top of the bats

42 and holes A, B and C are arranged at angles thereabove. Accordingly when water is supplied to tubular member 37 by way of conduit 21, a series of streams a, b, c and d emanating from the respective rows of holes A, B, C and D shoot outwardly to cover with a delicate shower of water all portions of the bats 42. It is to be particularly noted that the individual sprays forming the shower are generally in horizontal directions, as shown in Figure 3, and only drop a 10 short distance to reach the bats. Consequently the water forming the shower reaches the bat without undue force and, in fact, so gently as to avoid any damage to the body of the bats.

In the normal operation of my unique apparatus, tubular member 37 remains empty due to drain 40 (Figure 2) while valve 23 is closed. However, coil 21 is filled with water heated adequately by the water in tank 11 and ready for the next operation of the apparatus. Coil 21 is 20 preferably formed from a thin metal of high heat conductivity as, for example, copper, so that water contained therein may be quickly heated by the water in the tank.

The operator, after spreading the cloth upon 25 bench 14, places the group of bats 42 thereon. Before continuing with the starting operation he now depresses pedal 35, opening valve 23, and allowing water to flow into tubular member 37. A general shower of clean hot water falls upon 30 bats 42, the amount thereof being controlled by the length of time during which foot pedal 35 is depressed.

Upon releasing foot pedal 35, valve 23 closes to 35 stop the flow of water through coils 21 and the water remaining in tubular member 37 drains out into the tank by way of drain 40. The fresh supply of water in coil 21 is heated in a very short length of time by the water in tank 11. Thus 40 by the time the laborer has completed the operations on this group of bats and places a new group on bench 14, my apparatus is ready to produce a new shower of hot water in the manner described above.

Conduit 32, as explained above, may be connected to any suitable supply of water but is 45 preferably connected to the usual city supply thus to furnish clean water to my apparatus free from damaging particles of foreign matter. By locating the tubular member 37 on the left-hand 50 side of the operator, it does not inconvenience him as most of the operations which he performs on the bench, such as the rolling operation, are usually practiced in directions substantially from the right-hand outer corner to the left-hand 55 inner corner.

Referring to Figure 4, it will be seen that the farther stem 28a is depressed and consequently the farther foot pedal 35 is depressed, the greater 60 the amount of water passing through the valve and consequently the greater the intensity of the individual sprays forming the shower. Thus the operator may regulate the position of the shower with respect to the bench and may spray any portion of the bats 42 as may be desirable. For 65 example, if the left-hand side of the bats, as viewed in Figure 1, needs additional water, he applied very little pressure to the pedal and, conversely, if the right-hand side of the bats needs more water he opens the valve wide.

Accordingly it will now be seen that my apparatus materially reduces the labor of the operator thus to increase his efficiency and at the same time provides an efficient and practical method of spraying groups of bats in the start- 75

ing process free from the various difficulties hereinabove referred to.

As many possible embodiments may be made of the above invention and as many changes 5 might be made in the embodiment above set forth, it is to be understood that all matter hereinbefore set forth or shown in the accompanying drawing is to be interpreted as illustrative and not in a limiting sense.

10 I claim:

1. In hat machinery, in combination, a starting machine comprising a hot water tank and a bench adjacent the front side of said tank and sloping upwardly therefrom, means for supplying 15 hot water to said tank, a tubular coil extending through said tank, a source of water, a valve interposed between said source of water and said coil, means for actuating said valve, and a spray device connected to the other end of said coil 20 and associated with said bench, said spray device adapted to spray water on hat bats located on said bench upon the actuation of said valve.

2. In hat machinery, in combination, a starting machine comprising a hot water tank and a 25 bench adjacent the front side of said tank and sloping upwardly therefrom, means for supplying hot water to said tank, a tubular coil extending through said tank, a source of water, a valve interposed between said source of water 30 and said coil, means for actuating said valve, and a spray device secured to one side of said bench and connected to said coil whereby upon actuation of said valve said spray device showers hat bats on said bench with heated water from said 35 coil.

3. In hat machinery, in combination, a starting machine comprising a hot water tank and a bench adjacent the front side of said tank and sloping upwardly therefrom, means for supplying 40 hot water to said tank, a tubular coil extending through said tank, a source of water, a valve interposed between said source of water and said coil, means for actuating said valve, and a spray device secured to one side of said bench 45 and connected to said coil, said spray device being provided with a drain for discharging excess water upon the closing of said valve, whereby upon actuation of said valve said spray device showers hat bats on said bench with heated water 50 from said coil.

4. In hat machinery, in combination, a hat working machine including a tank of hot water and a bench extending from one side thereof, a conduit connected with a source of water extending 55 through said tank to be heated by the water therein, a tubular member secured to one side of said bench and connected to said conduit, said tubular member having formed therein a plurality of holes so placed as to provide a 60 shower of water over a section of said bench when water is supplied to said tubular member, and means for controlling the flow of water through said conduit.

5. In hat machinery, in combination, a hat 65 working machine including a tank of hot water and a bench extending from one side thereof, a conduit connected with a source of water extending through said tank to be heated by the water 70 therein, a tubular member disposed at one side of said bench and having rows of holes formed therein in such a position as to direct sprays of water upon all portions of a bat placed on said bench, and means for controlling the flow of water 75 through said conduit.

6. In hat machinery, in combination, a hat working machine including a tank of hot water and a bench extending from one side thereof, a conduit connected with a source of water extending through said tank to be heated by the water 5 therein, a tubular member disposed at one side of said bench and having rows of holes formed therein in such a position as to direct sprays of water upon all portions of a bat placed on said bench, said tubular member being provided with 10 a drain in the bottom portion thereof, and means for controlling the flow of water through said conduit.

7. In hat machinery, in combination, a hat working machine including a tank of hot water 15 and a bench extending from one side thereof, a conduit connected with a source of water extending through said tank to be heated by the water therein, a tubular member disposed at one side of said bench and having rows of holes 20 formed therein in such a position as to direct sprays of water upon all portions of a bat placed on said bench, a valve for controlling the flow of water through said conduit, and a foot pedal 25 connected to said machine for actuating said valve.

8. In hat machinery, in combination, a hat working machine including a hot water tank and a bench adjacent one side thereof, said bench sloping toward said tank, a source of water, a conduit connected to said source of water and extending through said tank, and a tubular member 30 connected to said conduit and extending along one side portion of said bench, said tubular member being provided with a plurality of rows of holes 35 so positioned as to form a shower of water on one portion of said bench when water passes through said conduit.

9. In hat machinery, in combination, a hat 40 working machine including a hot water tank and a bench adjacent one side thereof, said bench sloping toward said tank, a source of water, a conduit connected to said source of water and extending through said tank, a tubular member 45 connected to said conduit and extending along one side portion of said bench, said tubular member being provided with a plurality of rows of holes so positioned as to form a shower of water 50 on one portion of said bench when water passes through said conduit, and means for controlling the flow of water through said conduit.

10. In hat machinery, in combination, a hat working machine including a hot water tank and a bench adjacent one side thereof, said bench sloping toward said tank, a source of water, a conduit connected to said source of water and extending through said tank, a tubular member 55 connected to said conduit and extending along one side portion of said bench, said tubular member being provided with a plurality of rows of holes so positioned as to form a shower of water on one portion of said bench when water passes through said conduit, means for controlling the flow of water 60 through said conduit, and a foot pedal for actuating said last-mentioned means.

11. In hat machinery, in combination, a hat 70 working machine including a bench, a source of hot water, a tubular member extending along one side portion of said bench and connected to said source of water, and means connecting said tubular member to said bench, said tubular member being provided with a plurality of holes so positioned therein as to form a shower of water 75 on a portion of said bench to uniformly moisten

- baths preliminary to the positioning thereof in said machine.
12. In hat machinery, in combination, a hat working machine including a bench and a source 5 of hot water, a tubular member extending along one side portion of said bench and connected to said source of water, means connecting said tubular member to said bench, said tubular member being provided with a plurality of holes so positioned 10 therein as to form a shower of water on a portion of said bench, and means for controlling the flow of water from said source to said tubular member.
13. In hat machinery, in combination, a hat 15 working machine including a hot water tank and a bench adjacent one side thereof, a tubular member disposed at one side of said bench and provided with a plurality of holes so positioned as to form a shower on one portion of said bench, a 20 source of water, and a conduit connecting said source of water with said tubular member, said conduit being so positioned as to be heated by the water in said tank.
14. In hat machinery, in combination, a hat working machine including a hot water tank and a bench adjacent one side thereof, a tubular member disposed at one side of said bench and provided with a plurality of holes so positioned as to 5 form a shower on one portion of said bench, a source of water, a conduit connecting said source of water with said tubular member, said conduit being so positioned as to be heated by the water in said tank, and means for controlling the flow 10 of water through said conduit.
15. In hat machinery, in combination, a hat working machine comprising a hot water tank and a bench sloping upwardly from one side thereof, a source of water, a conduit passing 15 through said tank, and a spraying device connected to said conduit and disposed at one side of said bench, said spraying device adapted to shoot a plurality of individual sprays of water laterally with respect to said bench and thence 20 downwardly on a portion thereof.

RALPH K. REYNOLDS.
